MERCURY SWITCH RELAY

Carl J. Warmke, Elkhart, Ind., assignor, by direct and mesne assignments, to The Adams & Westlake Company, Chicago, Ill., a corporation of Illinois

Application February 1, 1932, Serial No. 590,004

1 Claim. (Cl. 175—375)

My invention relates to mercury switch relays and is directed more particularly to a device of this character in which an auxiliary circuit may be utilized, in conjunction with a mercury switch, 5 to interrupt a main or load circuit.

One object of my invention is to devise a relay comprising a transformer and a mercury switch in which the secondary winding is included in an auxiliary circuit which is conditioned to make or 10 break the load circuit through the switch dependent upon the strength of the current in the auxiliary circuit.

A further object is to provide a relay as indicated wherein the auxiliary circuit includes a 15 transformer secondary winding and an electromagnet for controlling the load circuit making and breaking positions of the mercury switch, the primary winding of the transformer being subject to a constant cyclic magnetization and 20 the operativeness of the electromagnet being dependent upon the strength of the magnetic field surrounding the electromagnet which in turn is dependent upon whether an air gap exists in the auxiliary circuit, corresponding to an opening 25 of the latter.

A further object is to devise a relay of the character indicated employing a mercury switch having a container which is maintained in an immobile state at all times, but is provided with 30 a movable part which acts in response to predetermined conditions for the purpose of making and breaking the circuit through the switch.

A further object is to provide a relay in which the movable part is formed of magnetic material and is utilized as the core of a solenoid, the presence of current passing through the solenoid, which is series connected with the secondary winding of the transformer, determining the 35 position of the movable part which corresponds to a circuit breaking position of the mercury switch, and the cessation of said current upon an interruption of the solenoid circuit permitting the part to fall under the action of gravity to complete the load circuit through the switch.

A further object is to devise a relay of the character indicated in which the auxiliary circuit is capable of being placed in an operative condition by relatively feeble currents, such as 40 those which may be made available by thermopiles, the sun's radiation, photo-electric cells, grid glow vacuum valves, and devices in general which are capacitated for the production of feeble currents only, so that the relay may be located in an environment in which feeble currents

only are available without affecting in any manner its capacity for adequate operation.

A further object is to devise a relay which is particularly adaptable for use under conditions requiring an indication of a change in temperature, such as ovens, furnaces, mechanical refrigerators, and the like, wherein variations in temperature affect the operation of other apparatus, and also under conditions where it is desired to operate certain apparatus at definite time intervals.

A further object is to provide a mercury switch relay employing a modified ironclad solenoid type of electromagnet which is arranged to materially lessen the iron losses due to eddy currents, so 70 that the relay is characterized by a high degree of sensitiveness, promptness of action and holding power.

A further object is the provision of a relay which is featured by a ruggedness in construction, long life, positive, efficient and dependable operation, and in which the composing materials are such as to substantially improve the operating characteristics of the switch relay relative to results now obtainable with devices of this type 80 in common use.

My invention is primarily intended as an arrangement comprising a transformer and a mercury switch which may be so conditioned and arranged in a load circuit that the latter itself 85 furnishes the energy required for its interruption, dependent upon conditions extraneous of the circuit. According to the present disclosure, the primary winding of the transformer is constantly energized, while the secondary winding is connected in series with an electromagnet that controls the circuit making or breaking positions of the mercury switch and also in series with some form of switch means, generically considered, whether of an electric or a mechanical type. As 90 long as the auxiliary circuit, consisting of the secondary winding and its associated elements, is broken at the switch means, a current will not be induced in the secondary winding so that the electromagnet will be unable to effect any operation of the mercury switch. However, promptly upon a closing of the switch means, the magnetic field established around the electromagnet by the induced current enables the latter to effect the desired operation. The relay may therefore be 95 regarded as embodying in some respects power boosting characteristics which become available merely by a closing of the auxiliary circuit, the energy for the magnetic field, however, being completely supplied by the main or load circuit.

100
105
110

The relay is therefore peculiarly adapted for use under conditions which are characterized by a delicacy of control and a relatively small amount of energy available for effecting the primary operation of the relay.

These and further objects of my invention will be set forth in the following specification, reference being had to the accompanying drawings, and the novel means by which said objects are 10 effectuated will be definitely pointed out in the claim.

In the drawings:

Figure 1 is an elevation of the relay as it appears in its enclosing casing, the cover of the latter 15 having been removed.

Fig. 2 is a section along the line 2—2 in Fig. 1, looking in the direction of the arrows, the cover being in position.

Fig. 3 is a side, sectional elevation of the relay, as viewed along the line 3—3 in Fig. 1, looking 20 in the direction of the arrows.

Fig. 4 is a sectional elevation of the mercury switch portion of the relay and its associated solenoid and laminated yoke, the switch being viewed 25 as it appears in Fig. 3.

Fig. 5 is a vertical, sectional elevation, somewhat enlarged, of the mercury switch container, the sleeve which functions as a core for the solenoid coil being shown in an elevated position, or 30 one which it would occupy when the solenoid coil is energized.

Fig. 6 is a diagrammatic illustration, partly in section, of the mercury switch container, and its associated laminated yoke and solenoid coil, the 35 parts being somewhat enlarged and viewed from the opposite side of the device as shown in Fig. 4.

Fig. 7 is a diagrammatic illustration, the mercury switch being partly shown in section, showing 40 the electrical connections of the relay.

Fig. 8 is also a diagrammatic illustration showing a modified circuit arrangement with which the relay may be utilized.

Referring to Fig. 5 of the drawings, the numeral 45 10 designates the container of the mercury switch portion of the relay, the same being generally elongated in shape and preferably composed of a glass that is characterized by a comparatively high melting point and a low coefficient 50 of thermal expansion relative to the lamp glass now used in the industry and which is therefore capable of withstanding the ravages of the electric arc when such occurs within the container upon the completion or breaking of the circuit. 55 In the present instance, magnesium silicate glass has been found suitable for this purpose in that it is substantially void of those materials, such as lead, tin, antimony, and substances generally which are decomposed under and by the action of 60 the electric arc and are picked up by or amalgamated with the mercury to thereby lessen its original state of purification and capacity for effective operation in the switch. Glass of the indicated type in addition possesses high tensile 65 strength, and sufficient elasticity to withstand and be substantially unaffected by rapid temperature fluctuations over wide ranges. It will be understood, however, that the indication of magnesium silicate glass being preferred for the 70 material of which the container 10 is composed is not to be considered as restrictive in nature, for the essential elements of the present invention reside in other features and combinations thereof.

75 The container 10 is provided with a lower end

wall 11 and is pinch-sealed at the opposite end, as at 12, in the customary manner. Prior to being sealed, it is contemplated that the interior thereof will be exhausted in accordance with standard practice, subsequent to the insertion of the parts presently described, and afterwards filled with one of the gases which are usually employed for the purpose of substantially suppressing the electric arc which tends to form when a circuit is made or broken in the switch, improving the heat conducting characteristics within the container, protecting the metallic electrodes from deterioration arising from ionization or from whatever cause, arresting the wetting or amalgamation of the electrodes by the mercury, and of keeping the electrode surfaces clean at all times. In the present instance, preformed helium hydride gas has been found entirely satisfactory for the indicated purpose, as in addition to incorporating the foregoing properties, it is also characterized by extreme stability and thus is particularly resistant to combination with most materials. However, as in the case of the material composing the container 10, I do not desire to be restricted by the foregoing suggestions as to the use of a gas fill, as other gases may be found entirely desirable and in view of the fact that the present invention is more particularly directed towards other features of construction. 90

Extending through the end wall 11 are lead-in wires 13 and 14, the material composing said wires being preferably that which is usually employed for the indicated purpose, such as dumet wire and the like, and the character of the seal between these lead-in wires and the glass container being such as to prevent leakage at the indicated point and said conductors being also preferably arranged, as regards their composing materials, that they are characterized by substantially the same coefficient of thermal expansion as the material forming the container 10. Within said container, an electrode 15 is suitably connected to the lead-in wire 13 and projects only slightly above the inner surface of the wall 11. A glass insulating sleeve 16 is fused 120 at one end to the wall 11 and the lead-in wire 14 extends upwardly therethrough for attachment to an electrode 17 which is disposed at a predetermined distance above the electrode 15 for a purpose presently explained. The precise 125 materials of which the electrodes 15 and 17 are composed form no part of the present invention, since standard practice may be adopted in this respect, although it is contemplated that, in any case, the material selected will be such as to offer 130 resistance to the erosive effects of the electric arc.

A mass of mercury 18 is placed in the container 10 to rest against the lower wall thereof and to be permanently in contact with the electrode 15, the length of the insulating sleeve 16 being sufficient in the position of parts as shown in Fig. 5 to prevent any contact of the mercury with the electrode 17, thereby preventing any passage of the electric current between the electrodes through the mercury. 140

A plunger 19 is mounted within the container, being generally cylindrical in shape and having a diameter somewhat less than the internal diameter of the container 10, so that an annular space 20 exists between the adjacent surfaces of the 145 container and plunger. The latter is further provided with a passage 21 which extends completely through the plunger in order to provide clearance for the sleeve 16 and the passage of mercury 150 upwardly therethrough in the manner presently

described. The plunger 19 is preferably formed of a material having a relatively high magnetic permeability, such as nickel, iron or equivalent material, or alloys formed of such materials, as well as of a material which is preferably resistant to the action of the electric arc. Between the ends of the plunger and the adjacent ends of the container 10, springs 22 are provided to cushion the shock that might otherwise obtain due to a free endwise movement of the plunger during handling or shipping. In addition to fulfilling its primary function of displacing a portion of the mercury in order to complete the circuit between the electrodes, as hereinafter described, it will be noted that, under such conditions, the plunger operates as a protective shield for the container 10, so that it is possible to utilize a cheaper grade of glass for the container, if such is desired.

Referring to Figs. 4 and 7, a solenoid coil 23 of any convenient type encircles the container 10 at a predetermined distance above the end wall 11 and from this coil extends the leads 24 and 25. The plunger 19 operates as the core of the coil 23 which thereby is enabled to function as a so-called sucking magnet when properly energized, the presence of a current passing through the solenoid producing a magnetic field which retains the plunger 19 in the position shown in Fig. 5, or generally in a position such that the mercury 18 is maintained free from contact with the electrode 17. Upon the cessation of the current passing through the coil, the plunger 19 will fall under the action of gravity and will be partly immersed in the mercury pool 18, as shown generally in Fig. 7. In the latter position the plunger 19 causes a rising of the mercury within the container upwardly through the annular space 20 and through the passage 21, until contact is established with the electrode 17, thus completing the circuit through the switch proper. Upon the reestablishment of a current condition through the solenoid 23, the magnetic field thus produced will retract the plunger 19 to the position shown in Fig. 5, thus breaking the circuit through switch.

In order to improve the operative characteristics of the mercury switch and render it capable of being operated by a relatively small current, while maintaining the required holding of the plunger 19, it is contemplated that a metallic return path will be provided for a considerable portion of the magnetic lines of force of the solenoid 23. To accomplish this result, a yoke 26 (see Figs. 3 and 4) composed of a plurality of thin sheets 27 (see Fig. 2) of iron or steel are secured together, each sheet having generally the profile of a reversed letter C, as viewed in Fig. 4. The end faces of the sheets 27 abut against an upper metallic sleeve 28 and a lower metallic sleeve 29 and are secured to the sleeves by means of clips 30 which encircle the same and are fastened to the yoke 26 by means of screws 31. The container 10 extends through the sleeves 28 and 29 and the former is made somewhat longer so that it may extend for a predetermined distance within the solenoid 23 in order to provide for an adequate magnetic coaction with the plunger 19. One convenient means of preventing slipping of the container in the sleeves until permanently installed is shown in Fig. 4 wherein the rubber rings 32 closely grip the container above and below the sleeves 28 and 29, respectively.

Referring next to the transformer unit of the relay, the numeral 33 designates this unit which is formed as an integral structure and which comprises a primary winding 34 and a secondary

winding 35, as illustrated diagrammatically in Fig. 7. In order to provide a common return path for the magnetic flux of the transformer windings, a yoke 36 is provided composed of a plurality of thin sheets 37 of iron or steel which are secured together by the screws 38, said laminations encircling the transformer unit 33 after the manner shown generally in Figs. 1 and 2.

The transformer and the mercury switch portion of the relay are mounted together in a convenient enclosure, together with their associated wiring and the necessary terminal posts. To accomplish this result, a pair of U-shaped brackets 39 and 40, upper and lower, respectively, as viewed in Fig. 1, are secured in spaced relation to the inside face of a casing 41. The right hand limbs of said brackets, as viewed in Fig. 1, support the mercury switch and its associated parts through being fastened to the yoke 26 by means of the screws 31. Similarly, the left hand limbs of said brackets support the transformer unit by being fastened to the yoke 37 through the medium of the screws 38.

A terminal board 42 is spaced from the back of the casing 41 by means of spacers 43 and secured thereto by means of screws 44. The terminal board 42 is provided with a pair of input terminals 45 and 46, a pair of output terminals 47 and 48, and a pair of auxiliary circuit terminals 49 and 50. In the form of hook-up shown in Fig. 7, the terminal 46 is connected by means of a lead 51 with one end of the primary winding 34, the opposite end of which is connected by a lead 52 with the terminal post 45. Accordingly, the primary winding 34 is bridged across any circuit to which the input terminals 45 and 46 may be connected. The terminal 46 is likewise connected by means of a lead 53 with the lead-in wire 13 of the mercury switch. The output terminal 48 is connected by means of a lead 54 with the lead-in wire 14, while the auxiliary terminal 49 is connected by means of a lead 55 with one end of the secondary winding 35, the opposite end of said winding being connected by the lead 24 to the solenoid coil 23 whose opposite end is connected by the lead 25 with the terminal post 50. In addition, for the arrangement of connections shown in Fig. 7, the terminal posts 45 and 47 may be connected by a lead 56, thus completing the circuit between the input terminals 45 and 46 and the output terminals 47 and 48 through the mercury switch when the plunger 19 is occupying the position shown in Fig. 7.

Under the foregoing conditions, it will be further considered that the auxiliary terminals 49 and 50 are connected externally of the switch by a suitable form of structure, whether of a mechanical or of an electrical nature, but which may be generally regarded as having circuit closing and opening characteristics, such as a switch means 57, generically considered. This switch means 57 may take the form of a clock mechanism, a thermostat, or any type of circuit which it may be desired to employ as a medium for controlling the opening or closing of the main or load circuit, of which the input and output terminals form a part.

With the circuit arrangement as indicated, it will be apparent that, notwithstanding the constant energization of the primary winding 34, the magnetic field established thereby will be insufficient, owing to the air gap existing in the auxiliary circuit provided by the opening of the switch means 57, to exercise any retractive effect on the plunger 19. However, promptly upon a

closing of the switch means 57, the solenoid coil 23 is immediately energized and pulls the plunger to the position shown in Fig. 5, or one in which the surface of the mercury pool 18 falls to a level 5 below the electrode 17, thus breaking the main circuit. The foregoing condition will be maintained so long as the switch means 57 remains closed, but promptly upon an opening thereof, the initial condition will obtain, namely, a cessation 10 of the magnetic field surrounding the solenoid coil 23, so that the plunger 19 will drop under the action of gravity into the position shown in Fig. 7, thus raising the level of the mercury pool into contact with the electrode 17 and again completing the load circuit.

In the modified circuit arrangement shown in Fig. 8, the input terminal 45 is not connected to the output terminal 47, but both input terminals are connected to the primary winding 34 in the 20 manner above described and said terminals connected to a suitable electric circuit which is independent of the circuit that is connected to the terminals 47 and 48. In the present instance, the terminal 47 is connected to the lead-in wire 14 by means of a lead 58, while the terminal 48 is connected to the lead-in wire 13 by means of a lead 59. The connections of the terminals 49 and 50 to the secondary winding 35 and the solenoid coil 23 are the same as outlined above in connection with the circuit arrangement shown in Fig. 7.

Accordingly, the primary winding 34 is sub-

jected to a constant cyclic magnetization from that circuit which is connected to the terminals 45 and 46 in the manner above described, but the indicated circuit is wholly independent of that circuit which is connected to the terminals 47 80 and 48. Upon a closing of the switch means 57, as stated above, the plunger 19 is withdrawn to interrupt the electric circuit through the terminals 47 and 48, while a contrary condition is established when the switch means 57 is open.

While I have shown one set of elements and combinations thereof for effectuating my improved relay, it will be understood that the same is intended for purpose of illustration only and in no wise to restrict the device to the exact 90 forms and structures shown, for many changes may be made therein without departing from the spirit of my invention.

I claim:

In a relay, a casing, a transformer in the casing including a secondary coil, a vertically disposed switch operating coil in series with the secondary coil, and a mercury switch associated with the operating coil and comprising a switch envelope, spaced electrodes in the envelope, a 100 quantity of mercury in the envelope adapted to make or break an electrical circuit through the electrodes according to its level, a displacer for determining the mercury level, said displacer being responsive to said secondary coil.
